(57) **CLAIM**

The ornamental design for a fuel pump, as shown and described.

DESCRIPTION

FIG. 1 is a perspective view of a fuel pump according to the present invention, taken from a lower front angle;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIGS. 1, 3, 6 and 7 are included for the purpose of illustrating portions of the fuel pump that form no part of the claimed design.
